(57) **CLAIM**

I claim the ornamental design for a fluted knob, as shown and described.

DESCRIPTION

FIG. 1 is a front perspective view of a first embodiment showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1; and

FIG. 8 is a cross-sectional view taken along line 8-8 of FIG. 2.

FIG. 9 is a front perspective view of a second embodiment showing my new design;

FIG. 10 is a front elevational view of FIG. 9;

FIG. 11 is a rear elevational view of FIG. 9;

FIG. 12 is a left side elevational view of FIG. 9;

FIG. 13 is a right side elevational view of FIG. 9;

FIG. 14 is a top plan view of FIG. 9;

FIG. 15 is a bottom plan view of FIG. 9; and

FIG. 16 is a cross-sectional view taken along line 16-16 of FIG. 10.

FIG. 17 is a front perspective view of a third embodiment showing my new design;

FIG. 18 is a front elevational view of FIG. 17;

FIG. 19 is a rear elevational view of FIG. 17;

FIG. 20 is a left side elevational view of FIG. 17;

FIG. 21 is a right side elevational view of FIG. 17;

FIG. 22 is a top plan view of FIG. 17;

FIG. 23 is a bottom plan view of FIG. 17; and

FIG. 24 is a cross-sectional view taken along line 24-24 of FIG. 18.

FIG. 25 is a front perspective view of a fourth embodiment showing my new design;

FIG. 26 is a front elevational view of FIG. 25;

FIG. 27 is a rear elevational view of FIG. 25;

FIG. 28 is a left side elevational view of FIG. 25;

FIG. 29 is a right side elevational view of FIG. 25;

FIG. 30 is a top plan view of FIG. 25;

FIG. 31 is a bottom plan view of FIG. 25; and

FIG. 32 is a cross-sectional view taken along line 32-32 of FIG. 26.

FIG. 33 is a front perspective view of a fifth embodiment showing my new design;

FIG. 34 is a front elevational view of FIG. 33;

FIG. 35 is a rear elevational view of FIG. 33;

FIG. 36 is a left side elevational view of FIG. 33;

FIG. 37 is a right side elevational view of FIG. 33;

FIG. 38 is a top plan view of FIG. 33;

FIG. 39 is a bottom plan view of FIG. 33; and,

(Continued)

FIG. 40 is a cross-sectional view taken along line 40-40 of FIG. 34.
